[57] CLAIM

The ornamental design for a backrest for use in a bathtub, as shown and described.

DESCRIPTION

FIG. 1 is a top plan view of a backrest for use in a bathtub showing my new design;
FIG. 2 is a side view thereof;
FIG. 3 is a bottom view thereof;
FIG. 4 is an elevational view taken from one end thereof;
FIG. 5 is an elevational view taken from the end opposite that shown in FIG. 4; and
FIG. 6 is a perspective view thereof.
